DOWEL SUPPORTING ASSEMBLY

William S. Godwin, Baltimore, Md.

Application June 10, 1944, Serial No. 539,679

15 Claims. (Cl. 94—51)

1
The invention relates to the assembling and holding in the assembled relation of the dowel units for concrete road joints and to the supporting of said dowels or units in their proper position prior to and during the pouring of the concrete.

Advantages and accomplishments of the invention include the provision of a main supporting plate extending along the joint the same being of hollow cross-section substantially throughout its length, whereby the individual dowel supports and the operating means are enclosed and protected from the soft, wet concrete which tends to foul these supports and operating means so that they would become difficult or impossible to disengage and remove without disrupting the concrete.

Another advantage is the provision of base-plates anchored to the sub-grade and supporting the main plate to prevent accidental movement of the dowels and sockets prior to and during the pouring of the concrete, the ends of the main plate preferably resting on said base plates on the sub-grade, or on suitable uprights which in turn rest on the base plates, supporting the main plate below the road surface.

A still further advantage is that the assembly is entirely below the tops of the side frames, free of the side frames and above the sub-grade, and thus independent of the irregularities of the sub-grade surface which may be soft or hard with contours, the dowel-supporting assembly of the invention resting on the positive hard level surfaces of base-supports or plates provided for this purpose and particularly where side-forms are used easily removable when pouring is completed.

A further and highly important advantage of the invention is that all moving parts are enclosed within the hollow or U-shaped support referred to as the main or cover-plate, and not exposed to the concrete.

The invention is illustrated in what at present is regarded as the preferred and a modified form, these forms being, however, for example only as showing two of various contemplated applications of the invention.

In the drawings

Fig. 1 is a side-elevation on a reduced scale of the dowel assembly in dowel-supporting position ready for the pouring of the concrete in the vicinity of a single road joint.

Fig. 2 is a section on the line 2—2 in Fig. 3 looking in the direction of the arrows, the plane of the figure being parallel to the plane of Fig. 1,

2
the structure shown being a single dowel-hook with the dowel engaged thereby and the supporting and actuating parts shown fragmentarily.

Fig. 3 is a section on line 3—3 in Fig. 2.

Fig. 4 is a horizontal section looking downwardly from the line 4—4 in Fig. 2.

Fig. 5 is a section corresponding to Fig. 2 taken at the end of the assembly adjacent to the side form or other paving.

Fig. 6 is a section on the line 6—6 in Fig. 5 looking in the direction of the arrows.

Fig. 7 is a top plan view looking downwardly at the assembly shown in the Fig. 1.

Fig. 8 is a view partly in section and partly in elevation looking in the direction of the arrows from the line 8—8 in Fig. 7.

Fig. 9 is a sectional elevation looking to the left from the line 9—9 in the Fig. 8.

Fig. 10 is a section corresponding to Fig. 2 showing a modified form of dowel-supporting hook.

Fig. 11 is a sectional elevation looking to the left from the line 11—11 in the Fig. 10.

Fig. 12 is a horizontal section looking downwardly from the plane indicated by the line 12—12 in Fig. 10.

Fig. 13 is a fragmentary vertical section showing a single socket and dowel in assembled relation in the concrete after the removal of the supporting assembly and the formation of the joint slot in the concrete.

Referring to the drawings by numerals, each of which is used to indicate the same or similar parts in the different figures and having particular reference to the forms illustrated in Figs. 1 to 9, the construction shown comprises a main support 10 or cover-plate, which in the preferred form shown is of inverted U-shaped cross-section. In slabs of ordinary width this extends from side to side, being supported at its ends preferably in a manner to be hereinafter described, or in wider roads there may be two or even three unit lengths of the assembly, the adjacent ends of the members 10 being supported intermediately on suitable bases on the sub-grade.

In the form shown the dowel supports, or dowel-supporting hooks 11 extend downwardly from supporting pins 12, see Fig. 2, which extend across the U-shaped member 10 from side to side, being for example welded or otherwise secured therein at their ends and extending through the horizontal slots 14 in the upper ends of the hook members 11 which are thus supported inside the U-shaped member 10.

These hooks 11, of which there is one for each

dowel, may have a depending shank or stem 15 which as shown is substantially vertical and may be tapered in horizontal section as at 11 in Fig. 4. This shank has at its lower end a transverse point or hook proper 16, shown as having a downwardly inclined upper surface 17 which engages beneath the dowel or dowel bar shown at 18, the end surface being shown as upwardly and forwardly inclined at 18'.

The hooks 11 in the preferred form shown have at the top a transverse or horizontally extending head portion 19 which as shown extends oppositely to the hook or points 16 in which head the slot 14 is formed. This transverse portion or head 19 which may be variously located in relation to the shank 11, is provided with spaced vertically extending lugs 20, 21 which are apertured in horizontal alignment at 22, and through these openings there is passed in a horizontal direction a hook-actuating rod 24. This may extend the length of the assembly having actuating members at its ends to be described, or it may be in two parts with actuating means at the center, as illustrated in Fig. 1, or be otherwise suitably arranged.

Between the lugs 21 and 22 there is in the form shown in the figures designated, an abutment collar 26 at the right and adjacent the latter, said collar 26 being mounted on and suitably secured to the rod 24. Between this collar 26 and the left-hand lug 20 in Fig. 1, which is on the side toward which the hook member or point 16 is disposed, there is shown a helical compression spring 27 which encloses the rod 24 bearing at one end against the collar 26 and at its other end against the left-hand lug 20, which as aforesaid is toward the direction of the point or hook member 16.

In the form shown in Fig. 1 the rod 24 is in two sections separated at the center and connected for simultaneous operation by a centrally pivoted lever 29 which is mounted on and within the main supporting plate 10 by means of a pivot pin extending from side to side of the same, in the manner of pins 12. The upper arm of this lever 29 is connected at its swinging end by a connecting rod 30 to the left-hand rod 24 and its opposite end is connected by connecting rod 31 to the rod section 24' at the right in Fig. 1. In this form of assembly it will be noted that the points of the hooks 11 at the left are disposed to the left and the points of the hooks at the right, indicated by reference characters 11', are disposed to the right, i. e. in the direction in which their respective points are advanced when lever 29 is rotated counter-clockwise, various arrangements whereby the hooks may be simultaneously engaged by movement of rod or rods 24, 24' being contemplated.

In this connection there is shown in Fig. 1 a leaf-spring 32 to engage the upper end of the lever 29 to restrain backward rotation from said engaged positions of the hooks. This or a similar device may be employed to hold the parts in normally engaged relation. Springs 27 equalize the pressure of the hooks 16 on dowels 18.

In the form shown the rod 24, 24' is provided at its ends which are normally adjacent the side-forms 33 with one or two operating heads 34 and 34'. In the form shown these heads are threaded on to the ends of the rod or rods 24, 24' of otherwise suitably secured. The heads 34, 34' are shown as slotted at 35 in the direction of the length of the rod 24, and they are also shown as provided with depending lugs 36 at their ex-

treme outer ends. An operating tool which is considered suitable to the purpose in hand is shown in Fig. 5 indicated by reference character 37.

Fig. 4 shows fragmentarily in plan a dowel 18 and socket 38 which may be in any suitable form. In the form shown the dowel is provided with a transverse flange 39 which may be secured thereto by means of a tongue 40 cut from the flange-plate 39 and bent outwardly and welded to the dowel 18 as shown, and the socket member 38 is shown as secured to the flange plate 41 in a similar manner, the precise form of dowel and socket being immaterial. The hook 11 is also shown with its shank 15 of a reducing taper in a horizontal plane and toward the dowel bar 18 so that it tends to have a wedging engagement between flange plates 39 and 41, and press these flanges outwardly against the legs of the U-shaped member 10 with a clamping action, Fig. 4.

The legs or sides of the U-shaped plate 10 are also shown in horizontal section in Fig. 4 at 42 and 43. These legs may be referred to as shields protecting the hooks and operating means from the concrete. This plate is shown in fragmentary vertical cross-section in Fig. 6, with one operating head 34 in elevation and the depending legs 42 and 43 in section. This figure also shows a pin 44 extending through the slot 35 in the operating head 34. The pin may be secured at its ends in the legs 42, 43 of the plate 10. Also the U-shaped plate 10 is shown as slotted as to the top cross-arm 43' of the inverted U 10 at the extreme ends of said plate 10, the slots in the form of plate shown, extending from the ends inwardly in the direction of the length of the actuating rod 24, the slots being indicated by reference character 45.

In the form shown the main cover-plate 10, which may be of any suitable cross-section to protect the individual dowel supports and the operating means therefor from the fluid concrete, is supported at its ends on base-plates 46 shown as having depending flanges 47 which extend downwardly into the sub-grade indicated at 48.

In the form shown, the details being for example only, the main or cover-plate 10 is provided at each end with a supporting device shown in the form of supporting-plates 50 which may be secured at their edges adjacent the horizontal top edges of the main or cover-plate 10, the secured edges extending for several inches along the supporting-plate 11 to its outer ends where the plates 50 are turned downwardly at right angles forming depending legs 51 as shown in Figs. 7 and 8, and also in Fig. 9, the vertical extent of the legs and the main plates 10 attached or assembled and measured from the top surfaces of base-plates 46 to the top of the plate 10, being less than the vertical extent of the side-forms 33.

These legs 51 are shown as reinforced at their lateral side edges with and by substantially vertical members shown as angle-irons 52 which extend downwardly along the supporting legs 51 and below the same at each side of the base-plates 46 as best shown in Figs. 8 and 9. The lower edges of legs 51 rest on top of base-plates 46 which are between the ends of bars 52, Fig. 7, reasonable variations as to details and arrangement being contemplated.

The plates 10 are shown as slotted upwardly from their lower edges forming dowel-slots, a socket like the one shown in Fig. 4 being illustrated as protruding from said slot 54 in Fig. 8. These slots are spaced in correspondence with the

desired spacing of the dowels and there is one hook 11 for each slot. The hooks in the preferred operation tend to press the dowels against the edges 54' of slots 54 whereby the dowels are spaced and positioned.

In Fig. 7 there is shown a section of relatively wide pavement, the width being greater than the length of the main or cover-plate 10. In this instance a base-plate 46 is placed beneath the adjacent ends of the two-cover plates 10 and the supporting members 50, 51, 52 rest thereon near the center of the plate substantially in the manner and relation thereto in which they are shown in Figs. 8 and 9. It may be noted at this point that the plates 46 are formed with a hole 56, as in Fig. 7, to be engaged with a hook-like instrument in removing the plates after the pouring of the concrete.

In assembling the dowels and sockets and support, the main plate or cover-plate 10 is inverted, the rod 24 being forced to the right in any suitable manner as by rapping on the lugs 36. If a second rod as 24' be provided, it is moved to the left in Fig. 1.

The dowel and socket units 18 and 38 are then assembled and pushed downwardly into the slots 54 which in that position of the plates 10 are open upwardly. As soon as all of the dowel and socket units are in place, the hooks 11 are engaged as by rotating the lever 29 contra-clockwise or left-handed and/or rapping the lugs 36, see Fig. 5, with a hammer, to the right in Fig. 5, the opposite lug being moved to the left as seen in Fig. 1, the parts being latched in the dowel-engaging position by the action of leaf-spring 32, or the hooks may be held in dowel-supporting position by the springs at all times except when the tool 37 is in position. If a single rod 24 be employed, the hooks being disposed in a single direction, the operation will be apparent from the foregoing, or the dowels may be forced into slots 54 thus engaging inclined surfaces 18' and moving the hooks to withdrawn position, whereon the dowels pass the hooks and the springs cause the engagement of the latter with the dowels. When the dowel-supporting assembly is thus completed, all of the working parts, whereby the dowels are engaged and disengaged, are enclosed within the U-shaped member 10 or cover-plate and thus protected from accumulation of concrete and other detrimental occurrences resulting from exposure.

The dowel-supporting assembly thus completed, is ready to be set up in the roadway as illustrated in Figs. 1 and 7 to 9. For this purpose a base-plate 46 suitably leveled is either pushed under the side-form 33 as shown in Fig. 1 or under the finished paving 58 as shown in Figs. 7 and 8. The depending flanges 47 of plates 46 extend downwardly into the sub-grade holding the base plates and preventing lateral displacement of the assembly.

The main supporting, or cover-plate 10, when thus assembled with the dowels and sockets, if used, said plate is placed in position at right angles to the direction of the road, with the legs 51 preferably resting on the plates 46 and the angles 52 extending downwardly at each side of the base-plates 46. The laterally elongated bottom edge 51' of leg plate 51 resting on base plate 46 prevents tipping of the dowel-supporting assembly. By suitable leveling of the base plates 46, or by merely placing them directly under the side molds 33, the member 10 is leveled and also suitably located slightly below the road surface

and out of the way of the finishing machine, the members 46 to 52 being of suitable length.

Immediately thereafter the concrete may be poured and as soon as the leveling machine has been run over the work, the supporting assembly 5 may be removed. In this connection it will be understood that the finished surface of the road is normally in the plane of the top surfaces of the side forms 33, which according to the preferred operation and arrangement of applicants' device, is above the top of cover-plate 10, supported in the manner described.

To this end a suitable tool, a satisfactory form of which is shown at 37 in Fig. 5, is inserted through the slots 45, the operating heads 34 being forced inwardly or to the right in Fig. 5, whereby the tension of springs 27 is relaxed and the collars 26 are brought in contact with the lugs 21 releasing the hooks 11 which are moved to the right in Fig. 2 or to the right and left respectively in Fig. 1, from the dowel. The operation described whereby the actuating head 34 is moved to the right in Fig. 5 and/or 34' to the left, tends to rotate the lever 29 in a clockwise direction with a corresponding motion of the rods 24, 24' in Fig. 1 and releasing the hooks 11 and 11'. This arrangement is not essential to other features.

It is of importance, as already pointed out, that all the moving parts are protected by and enclosed within the cover-plate or main plate 10 which, when the support is thus released, is raised most easily by engagement of the tool 37 in the slot 45 and immediately thereafter the concrete, due to its tendency to flow, closes the opening left by said plate 10, in place of which a slot like that shown at 59 in Fig. 13 is generally made by means of a suitable tool.

It is of importance that the dowels and sockets are not only supported on plate 10 but are spaced and positioned by slots 54 therein and that cover-plate or dowel-holder 10 may be entirely below the tops of the side forms out of the way of the finishing machine and above the sub-grade, and that all of the dowel-holders or latches may be moved in unison, and particularly that the main-plate or cover-plate is supported not only on the sub-grade but on suitable, preferably, removable base-plates which can to advantage be suitably leveled, with regard to the road surface and without reference to the condition of the sub-grade. These base-plates anchored in the manner shown prevent lateral movement of the dowel-holders. They may be otherwise located.

It is also of interest that the engagement of the wedge-shaped shanks 15 with the flanges 39, 41 has a locking effect which may assist or be independent of the spring 32 and may be employed to prevent premature release of the hooks 11, and that as shown in Fig. 8, the operation of the hooks 11 and the springs 27 force the dowel members 18 against the sides 54' of the slots 54 which are forward in the direction in which the hook points 16 are disposed. These sides or edges 54' may be relied on to space the dowels according to a predetermined standard.

Referring now to Figs. 10, 11 and 12, these figures disclose a second form of dowel-hook which may be treated as embodying various features of the invention.

This hook indicated by reference character 60 is in the form referred to pivoted intermediately to swing about a transverse stud or pin 61 which extends through the cover-plate from side to side, being suitably secured in or to the side-plates 42 and/or 43 thereof, the said hook member 60 being

between said plates. The hook member 60 is shown in the form of two arms radiating from the pin 61, one, 62, disposed upwardly and the other, 63, downwardly and to the left in Fig. 10, half of the said arms 63 being, according to the illustration in Fig. 1, oppositely inclined.

The upper arms 62 are shown as having double-forks 64 at their upper ends which receive and enclose the hook-actuating rod 24, which in the form shown is provided with transverse pins 65 suitably secured thereto to engage said hooks 64, which in the form shown, straddle or embrace both the rod 24 and the pin 65.

The lower arms 63 are shown in Figs. 10, 11 and 12 as provided at their swinging ends with hook members, or points 66 and the side plates have abutments 66', which are adapted to engage the bottom and side surfaces of the dowel members 18, when a suitable tendency is imparted to said arms 63 to swing upwardly or laterally, against the lower side of the dowel.

In the form shown the arms 63 have seated therein, or otherwise suitably secured, a spring 67 which in the form shown is of inverted U-shape, the forward arm of the U at 67' serving to press against the adjacent side of the dowel 18 when the arm 63 is swung up to the engaging position of hook member 66, whereby a yielding effect is obtained, to equalize the hook action.

In both forms of the invention, the rod 24 may be operated from either end in a single direction or from either end or the center in both directions as suggested and illustrated in Fig. 1 and other figures.

In operation the main-supporting plate, or cover-plate 10 is first inverted as previously described, and the assembled socket and dowel units are moved downwardly into the corresponding notches 54 and at this time the hooks 60 are moved as by action of the rod or rods 24 or by yielding so that the dowels are easily admitted. Immediately thereafter all of the hooks simultaneously or separately engage with the dowels and the dowels being thus engaged and held in position, the assembly is returned to upright and located in the work, i. e. on the sub-grade and in line with the proposed joint, the concrete is poured and the entire assembly is removed substantially as described in connection with Fig. 1, etc.

Having thus described a preferred and modified form of dowel-supporting structure as examples of the nature and method of practice or application of the invention, I would have it understood that various modifications and changes of form and arrangement, such as would occur to a designer or engineer familiar with this disclosure, are contemplated.

What I claim as new and desire to secure by Letters Patent is:

1. A dowel-supporting assembly for concrete road joints comprising an elongated hollow main plate, dowel spacing means for a plurality of dowels spaced along said plate, dowel supporting members, means mounting said members within said main plate adjacent said spacing means for movement between two positions, each of said members in one position holding a dowel within one of said spacing means and in the other position releasing the dowel therefrom, a common operating means enclosed within the main plate and extending longitudinally thereof, and means operatively connecting said operating means to a plurality of said members.

2. In a device as claimed in claim 1, spring

means urging said members toward dowel holding position, said members having inclined surfaces engageable by a dowel during insertion into said spacing means to move the members away from dowel engaging position.

3. In a device as claimed in claim 1, spring means urging said members toward dowel holding position, said members having wedges engageable between flanges on dowel assembly, whereby to center a dowel assembly engaged thereby.

4. A dowel supporting assembly for concrete road joints comprising an inverted channel-shaped member having side walls having slots extending upwardly from the bottom edges thereof at points spaced longitudinally thereof to receive dowels, dowel supporting members, and means mounting said supporting members within the channel of said channel-shaped member at points above the upper ends of said slots for movement between positions in which the supporting members hold dowels in the slots and positions in which they release dowels therefrom.

5. A dowel supporting assembly for concrete road joints comprising an inverted channel-shaped member having side walls having slots extending upwardly from the bottom edges thereof at points spaced longitudinally thereof to receive dowels, dowel supporting members, means mounting said supporting members within the channel of said channel-shaped member for movement between positions in which the supporting members hold dowel members in the slots and positions in which they release dowels therefrom, a common operating means for said supporting members within the channel of said channel-shaped member above the upper ends of said slots, and means operatively connecting said operating means to said supporting members.

6. A dowel supporting assembly for concrete road joints comprising an inverted channel-shaped member having side walls having slots extending upwardly from the bottom edges thereof at points spaced longitudinally thereof to receive dowels, dowel supporting members, means mounting said supporting members within the channel of said channel-shaped member at points above the upper ends of said slots for movement between positions in which the supporting members hold dowel members in the slots and positions in which they release dowels therefrom, a common operating means for said supporting members within the channel of said channel-shaped member, and means operatively connecting said operating means to said supporting members.

7. A dowel supporting assembly for concrete road joints comprising an inverted channel-shaped member having side walls having slots extending upwardly from the bottom edges thereof at points spaced longitudinally thereof to receive dowels, dowel supporting members, and means mounting said supporting members within the channel of said channel-shaped member spaced inwardly from the side walls thereof for movement between positions in which the supporting members hold dowels in the slots and positions in which they release dowels therefrom, said supporting members being engageable between flanges on a dowel assembly to hold said flanges against the side walls whereby to close said slots.

8. A dowel supporting assembly for concrete road joints comprising an inverted channel-shaped rigid member having substantially plane side walls having slots extending upwardly from the bottom edges thereof at points spaced longitudinally thereof to receive dowels, means for sup-

porting said assembly spaced above a sub-grade, dowel supporting members, and means above the upper ends of said slots mounting said supporting members within the channel of said rigid member spaced inwardly from the side walls thereof for movement between positions in which the supporting members hold dowels in the slots and positions in which they release dowels therefrom, said supporting members being engageable between flanges on a dowel assembly to hold said flanges against the side walls whereby to close said slots.

9. A dowel supporting assembly and dowel structure for concrete road joints comprising an inverted channel-shaped rigid member having substantially plane side walls having slots extending upwardly from the bottom edges thereof to points spaced longitudinally thereof to receive dowels, dowel structures each comprising a pair of members adapted to be embedded in opposite sides of a road joint and slidably mounted with respect to one another, said members having flanges thereon adjacent the points which lie in the adjacent faces of the joint, dowel structure supporting members, means mounting said supporting members within the channel of said rigid member spaced inwardly from the side walls thereof for movement between positions in which the supporting members hold dowel structures in the slots and positions in which they release dowel structures therefrom, said supporting members being engageable between said flanges to hold said flanges against the side walls whereby to close said slots.

10. In a device as claimed in claim 7, said supporting members having parts wedge shaped in cross-section engageable with said flanges to position the dowel laterally with respect to said rigid member.

11. In a device as claimed in claim 9, said supporting members having parts wedge shaped in cross-section engageable with said flanges to position the dowel structure laterally with respect to said rigid member.

12. A dowel supporting assembly for concrete road joints comprising an inverted channel-shaped member having side walls having slots extending upwardly from the bottom edges thereof at points spaced longitudinally thereof to receive dowels, dowel supporting members, means mounting said supporting members within the channel of said channel-shaped member for movement between positions in which the supporting members hold dowel members in the slots and positions in which they release dowels therefrom, the supporting members in opposite halves of said channel-shaped member moving in opposite directions to holding and releasing

positions respectively, a common operating means for said supporting members, means mounting said operating means within the channel of said channel-shaped member for movement longitudinally therein, and means operatively connecting said operating means to said supporting members.

13. In a dowel supporting assembly for road joints having a slot in the bottom edge to receive a dowel, a dowel supporting member, means mounting said member adjacent said slot for movement with respect thereto, said member having a part engageable beneath a dowel structure within said slot and a stem connecting said part to said mounting means, said stem being wedge shaped in cross-section to engage between flanges on a dowel structure held in said slot.

14. In a dowel supporting assembly for concrete road joints, a dowel supporting member, means mounting the supporting member in said assembly for movement between dowel holding and dowel releasing positions, means on the dowel supporting member engageable with a dowel to shift the same laterally of the assembly for centering, and resilient means urging the supporting member into dowel engaging and holding position.

15. A dowel supporting assembly for concrete road joints comprising an inverted channel-shaped member having side walls having slots extending upwardly from the bottom edges thereof at points spaced longitudinally thereof to receive dowels, dowel supporting members, and means mounting said dowel supporting members within the channel of said channel-shaped member for movement between positions in which the supporting members hold dowels therefrom, said supporting members having parts wedge shaped in cross-section engageable with a dowel to space the same laterally with respect to said member.
